UNITED STATES PATENT OFFICE.

JACOB G. HARTMAN, OF BALTIMORE, MARYLAND.

COIN-CONTROLLED ELECTROMEDICAL BATTERY.

SPECIFICATION forming part of Letters Patent No. 674,336, dated May 14, 1901.

Application filed January 24, 1900. Renewed October 17, 1900. Serial No. 33,405. (No model.)

To all whom it may concern:

Be it known that I, JACOB G. HARTMAN, a citizen of the United States, residing at Baltimore, in the State of Maryland, have invented 5 certain new and useful Improvements in Coin-Controlled Electromedical Batteries; and I do hereby declare the following to be a full, clear, and exact description of the invention, such as will enable others skilled in the art to which it 10 appertains to make and use the same.

This invention relates to machines of the class in which persons depositing a suitable coin in a slot may receive an electric current for a predetermined period of time.

15 The apparatus involves an induction-coil, a battery making circuit through both helices of the coil and including in both circuits conducting-handles electrically connected by the person of the user, and means for making and 20 breaking both circuits at proper times and for varying at will the intensity of the induced current.

25 In the drawings, Figure 1 is a rear elevation of the apparatus, the rear portion of a certain inclosing case or box being removed. Fig. 2 is a similar front elevation of the box, showing the handles, coin-slot, and indicator. Figs. 3, 4, 5, 6, 7, 8, and 9 are detail views, herein-after referred to.

30 In the views, A represents a normally locked wooden case having in its front a coin-slot A', a glass-covered index A², and provided with conducting-handles A³ A⁴, whose spindles A⁵ A⁶ pass through heavy sleeves A⁷, 35 strongly secured in apertures in the case. The spindle A⁵ of the handle A³ is fixed in its sleeve by a set-screw A⁸ or the like, while the spindle A⁶ of the other handle A⁴ is arranged to rotate through an angle of less 40 than three hundred and sixty degrees, the rotation being limited by a lug A⁹ on the spindle normally lying at one limit of a partial annular recess A¹⁰ in the outer face of the corresponding sleeve A⁷. By this means 45 mischievous persons having great strength are prevented from straining any working parts within the case, and to prevent loosening of the sleeve itself it is made with flanges A¹¹. Over the inner end of the spindle A⁵ a 50 perforated metal plate C is passed and rigidly secured to the inner face of the front to support various parts to be described, and upon

the same spindle a conducting cam-hub D is next pressed against the plate C and secured by a set-screw D', thus preventing the withdrawal of the spindle. The inner end of this spindle has a bearing in a conducting-post E, which carries an insulated spring contact-piece E'. A segment D² of a pulley is formed integrally with the hub D and normally lies 55 out of contact with the piece E', but in such position that as the handle A⁴ is rotated the side face of the segment strikes and rubs along this piece until the limit of the handle's rotation is reached. When the handle is released 60 after rotation, a spring E² instantly restores it to normal position. Upon the plate C is pivoted a lever F, notched below to engage the end face F' of an annular shoulder F² upon one face of the segment D² and provided with a 65 variable counterweight F³ to hold it in engagement. Upon the opposite end of the lever F a coin-receiving cup F⁴ is so mounted that it may 70 rotate about the end portion of the lever as an axis, yet will normally be held upright by 75 gravity, which swings its side against the front wall of the case, or, in other words, the line of gravity of the cup lies considerably nearer the case than its axis of rotation. Coins inserted in the slot A' are guided into 80 this cup by a chute G, and a coin of proper weight will overbalance the counterweight F³, tilt the lever, and leave the knob free to rotate. As soon as rotation carries the end face 85 F' past the notch in the lever the shoulder F² supports the lever and relocking is impossible until the knob returns to normal position. Another lever H is pivoted at H' to the same plate C to swing in a vertical plane 90 passing between the lever F and the case front. This lever is curved upward immediately over the spindle A⁶, and its non-curved portion H² normally rests upon the flattened upper side D⁴ of the hub D. The rotation of the hub (to the left in Fig. 4) suddenly 95 raises the free end of this lever, causing it to strike the coin-receptacle, tilting it and discharging the coin therein into the hopper H³ of a rearwardly-open chamber H⁴, containing a coin-box H⁵, removable, without exposing 100 the working mechanism, through a small door (not shown) in the rear wall of the box A. As soon as the non-flattened portion of the hub is made to support the lever the latter

ceases to rise and is held stationary during the further rotation of the knob.

The electric current in this apparatus is supplied by a battery I and an ordinary commercial induction-coil I', the primary circuit being from the battery through the primary helix of the coil, wire I², handle A³, person of the user, handle A⁴, spindle A⁶, segment D², piece E', and wire I³, and the secondary circuit being through the secondary helix and the same route to the spindle A⁶, thence through the post E, wire J, spring contact-piece K upon the front of the case, post K', and wire K². Circuit being completed by seizing both knobs and bringing the segment D² into contact with the contact-piece E', it is maintained until the knobs are released or until at the expiration of a predetermined period of time it is automatically broken at the post K' by devices to be described. To thus break it, I provide a small spring-motor, which is wound by the turning of the knob, and which then after running for a certain time breaks the circuit by pushing the spring K from the post K'.

The motor itself is without novelty, being operated by the power of a spring L⁰ acting upon a shaft L. Upon this shaft is fixed a collar L', having an arm L², which as the shaft rotates strikes the spring contact-piece and pushes it from the post K', breaking the secondary circuit. It also has a short arm L³, to which is pivoted a pawl L⁴, whose weight normally holds it against a stop L⁵, which limits the swing of the pawl upon its pivot in one direction, while a stop L⁶ limits the movement in the contrary direction. The free end of the lever H normally lies just below the end L⁷ of the pawl, and when the knob A⁴ is rotated, lifting this lever in the manner already disclosed, the pawl, which cannot swing on its pivot, since it rests against the stop L⁵, is forced upward until it passes out of the lever's path, allowing the latter to rise above it. The shaft L is thus rotated through a small angle, winding the spring L⁰ thereon and carrying the arm L² to some distance from the contact-piece K and leaving the latter in contact with the post. As soon as the lever has released the pawl the spring begins to return the arm L² slowly toward the spring K, the ordinary fan M limiting the speed of movement. At the expiration of a predetermined time—as, for example, one minute—the arm will push the spring from the post and the motor will be arrested by a stop O, fixed to the motor-frame in the path of a projection N upon the collar. The current being thus interrupted and the handles being released, the spring E² returns the rotary knob to normal position, allowing both levers F H to fall. As the lever F descends gravity restores the coin-receptacle on its end to upright position, and as the lever H approaches its lower limit it tilts the pawl and passes it, the stop L⁶ properly limiting the tilting movement. That the strength of the induced current may in-

crease with the rotation of the handle, and thus the amount of rotation may be indicated, a cord P is attached to the periphery of the segment D² and also to the periphery of a drum Q, fixed to the inner portion of the shaft R of the index A², and from the same drum a cord S passes over a pulley S' and is attached to the sleeve of the induction-coil. Obviously the index will be rotated and the sleeve will be withdrawn in proportion to the rotation of the knob-spindle.

From the construction it is plain that a proper coin holds the knob unlocked until the knob has been turned and current has been obtained, so that no mistakes can be made by users, and while a user may have the current for the full time he must use it continuously. If he makes the current too strong and must release the knob before the lapse of the full time, generation ceases and so much current is saved. Nor is there any possibility of one or more persons obtaining current for more than the proper time for one coin. In other words, less but not more than the maximum may be taken.

As the motor runs but a very brief time, only a very short spring is used, and although usually unaware of the fact the user necessarily winds that spring as much as it unwound during the last preceding use.

Changes in details of construction may be made without passing the limits of my invention, and I do not therefore desire to limit my claims to the forms chosen for illustration.

What I claim is—

1. In apparatus of the class described, the combination with a suitable case having conducting external handles one of which is rotatable but normally locked, of a battery within the case arranged to make circuit through the handles, means whereby rotation of one handle may make and break the circuit, an induction-coil having its primary helix in the battery-circuit and its secondary terminals connected with the handles, respectively, means whereby a coin unlocks the rotary handle, and devices arranged to automatically break the secondary circuit at a fixed interval after the closing of the battery-circuit.

2. In apparatus of the class described, the combination with a fixed and a normally locked rotary conducting-handle, of a battery making a normally open circuit through the handles, means whereby the rotation of the one handle closes the open circuit, a spring resisting such rotation, and rigid stops limiting such rotation in each direction.

3. The combination with two conducting handles one of which is rotatable of a battery and an induction-coil both making normally open circuit through said handles, a spring resisting rotation of the one handle, a weighted lever normally locking said handle against rotation, means for causing an inserted coin to rest upon said lever to overbalance the same and unlock the handle, means whereby

rotation of the handle discharges the coin from the lever.

4. In apparatus of the class described, the combination with the conducting knobs or handles one of which is rotatable, of a curved index, and a battery and an induction-coil both making circuit through the person grasping said handles, and a cord connected with both the index and the sleeve of the induction-coil and wound by rotation of the handle, whereby the rotation of the handle governs the current and shows its intensity.

5. The combination with a suitable casing provided with external conducting-handles one of which is rotatable but normally locked, of current-generating devices within the casing arranged to make circuit through the

handles on the closing of a break within the casing and the connecting of the handles through the person of the user, means for unlocking the handle, means whereby the rotation of the handle closes the break within the casing, a motor, means whereby the rotation of the handle puts the motor in operation, and means whereby the motor in operating breaks the circuit after a predetermined interval.
